UNITED STATES PATENT OFFICE.

FRANK J. TERRELL, OF WATERBURY, CONNECTICUT, ASSIGNOR TO THE HOGE MANUFACTURING COMPANY, INC., OF NEW YORK, N. Y., A CORPORATION OF NEW YORK.

DESIGN FOR A PENCIL.

•0,479.

Specification for Design. Patented Feb. 21, 1922.

Application filed July 9, 1920. Serial No. 395,161. Term of patent 3½ years.

To all whom it may concern:

Be it known that I, FRANK J. TERRELL, a citizen of the United States, residing in Waterbury, in the county of New Haven, State of Connecticut, have invented a new, original, and ornamental Design for Pencils, of which the following is a specification, drawing, forming a part thereof.

Fig. 1 is a side elevation of a pencil showing my new design, looking directly toward the clip; and Fig. 2 is a side elevation with the pencil turned 90°.

I claim:

The ornamental design for a pencil, as reference being had to the accompanying drawing, forming a part thereof.

FRANK J. TERRELL.
